UNITED STATES PATENT OFFICE.

WORTHEY H. NEWELL, OF GULF HAMMOCK, FLORIDA.

ROTARY STEAM ENGINE.

Application filed June 18, 1927. Serial No. 199,717.

The present invention relates to a rotary steam engine and has for its prime object to provide a ring-like casing with pistons movable therein and connected with a rotary disc 5 or the like on a shaft and valve means for controlling the inlet and outlet of the steam and abutments for allowing the steam to expand between the abutments and the pistons to provide the rotary motion, and 10 means for operating the abutments and valves in unison.

Another very important object of the invention resides in the improvement of the arrangement of the parts to provide a comparatively simple structure which is thoroughly efficient and reliable in operation, and otherwise well adapted to the purpose for which it is designed.

With the above and numerous other objects in view as will appear as the description proceeds, the invention resides in certain novel features of construction, and in the combination and arrangement of parts as will be hereinafter more fully described 25 and claimed.

In the drawing:

Figure 1 is a sectional elevation of the engine embodying the features of my invention,

30 Figure 2 is a sectional view therethrough taken substantially on the line 2—2 of Figure 3;

Figure 3 is a sectional view taken substantially on the line 3—3 of Figure 2,

35 Figure 4 is a sectional view taken substantially on the line 4—4 of Figure 2,

Figure 5 is a sectional elevation of the packing adjusting means,

40 Figure 6 is a face view of one of the valves.

Referring to the drawing in detail it will be seen that the numeral 5 denotes a shaft with a disc 6 fixed thereto. A casing comprises ring-like sections 7 and 8 which are secured together by bolts 9 or in any other suitable manner. The inner edges of the casings are provided with annular extensions 10. The disc 6 extends between the extensions 10 and the inner edges of the sections 7 and 8 and has flanges 11 which extend into the extensions 10. Annular packing 12 is disposed in the extensions and held against the lower edges of the sections 7 and 8 and against the flanges 11 by means of bolts 14 threaded into the extensions 10 and having their interior ends hollow as is indicated at

15 to receive packing engaging elements 16 which are spring pressed outwardly as at 17. Lock nuts 18 are provided on the bolts 14 so that after being adjusted they may be 60 locked against accidental displacement. On diametrically opposite sides of the disc 6 there are formed pistons 19, in the present instance, two in number. These pistons 19 are movable in the casing formed by the 65 sections 7 and 8. The section 8 is formed in the present instance with three housings 20 having removable covers 21. These housings are formed with a central compartment 22 and side compartments 23 and 24, the 70 latter two forming steam chests. An inlet pipe 25 leads to the steam chest compartment 23 and an exhaust steam pipe 26 leads from the exhaust steam chest compartment 24. Passages 27 have apertured communications 28 with the interior of the casing formed by sections 7 and 8 and with the steam chest 23 through apertures 29. A valve 30 is slidable in the chests 23 and has passages 31 which may be brought into registry with apertures 29 to allow the steam to pass through the passage 27 and apertures 28 into the main piston casing. A valve 32 is mounted in the chest 24 and has 75 passages 33 which may be brought into registry with apertures 34 leading into a passage 35 apertured in communication with the piston casing as at 36.

All of the casings or housings 20 are of identical construction and for the purpose of clearness, only one will be referred to in detail as far as the specific structure is concerned. A cam element 40 is keyed 90 on the shaft 5 and has cam humps 41 at diametrically opposite points in alignment with the pistons 19. A rod 42 is slidable through a bearing 43 in the inner end of the housing 20 and has a yoke 44 engaged therewith in any suitable manner and having its branches extending up through bearings 45 into the chests 23 and 24 and has the extremities of the branches formed with lateral extensions loosely engaged with the valves 30 and 32. A spring 46 is disposed about the rod 42 and normally holds the rod downwardly with its roller 47 in engagement with the periphery of the cam element 40. The upper end of the rod 42 has a roller 48 which is engaged in an arcuate slot 49 of the shank 50 of an abutment 51 the shank being pivoted at its extremity as at 52. When the roller 47 is at the top 100

105

110

of one of the humps 41 the abutment 51 is swung into the compartment 22 as is illustrated in Figure 3, and of course at this time one of the pistons 19 is passing by the housing 20. As soon as the piston passes by and the roller 47 slips off the hump 41 the abutment 51 is swung back into the casing and the steam will expand between this abutment and the piston which has just passed 10 by.

The details of construction have been described with sufficient particularity to now appreciate the full operation of the engine. The shaft, in Figure 1, is rotating in a counter-clockwise direction and as is apparent from Figure 2 one of the pistons namely the upper piston has just passed the uppermost housing 20 so that steam is entering through the inlet 25, steam chest 23, and as soon as 15 the roller 47 moves completely off the hump 41 said steam will pass through passages 31 and openings 29 into passage 27 and through apertures 28 to expand between the uppermost abutments and the uppermost pistons 20 and drive said piston in Figure 2 in a counter-clockwise direction as said lower piston is being driven from the lower left-hand housing 20 as will be apparent without further detailed description. It is to be noted 25 that the exhaust passages are always open since the steam exhausting outwardly through the passages 34 maintains the valve 32 pushed back so that the passage is free. In the same way the intake steam maintains 30 the valve 30 in abutment with the wall in which the openings 29 are provided. It will be apparent that the steam may be entered through the pipe 26 and allowed to exhaust through the pipe 25 for reversing 35 the engine.

It is thought that the construction, operation, and advantages of this invention will now be quite apparent to those skilled in this art without a more detailed description 40 thereof. The present embodiment of the invention has been disclosed in detail merely by way of example since in actual practice it attains the features of advantage 45 enumerated as desirable in the statement of the invention and the above description.

Having thus described my invention, what I claim as new is:

1. A rotary steam engine of the class described comprising a ring-like hollow casing, a piston movable in the casing, a housing on the casing formed with a central compartment and a pair of steam chests one to each side of the central compartment, said housing provided with passages leading from the steam chests into the interior of the casing, a pair of valves one in each chest, a yoke having its extremities slidable in the chests, means for providing a loose connection between the extremities of the yoke and the valves, steam intake means associated with one chest, steam exhaust means associated with the other chest, said valve formed with passages to register with the passages first mentioned, the inlet valve being held in operative position by the incoming steam and the exhaust valve being held in inoperative position by the exhaust steam because of the loose connections with the yoke. 55

2. A rotary steam engine of the class described comprising a ring-like hollow casing, a piston movable in the casing, a housing on the casing formed with a central compartment and a pair of steam chests one to each side of the central compartment, said housing provided with passages leading from the steam chests into the interior of the casing, a pair of valves one in each chest, a yoke having its extremities slidable in the chests, means for providing a loose connection between the extremities of the yoke and the valves, steam intake means associated with one chest, steam exhaust means associated with the other chest, said valve formed with passages to register with the passages first mentioned, the inlet valve being held in operative position by the incoming steam and the exhaust valve being held in inoperative position by the exhaust steam because of the loose connections with the yoke. 60
